(57) **CLAIM**

The ornamental design for a thumb guard as shown and described.

DESCRIPTION

FIG. 1 is a first perspective view of a thumb guard showing my new design;

FIG. 2 is a side view thereof;

FIG. 3 is a top view thereof;

FIG. 4 is a second perspective view thereof arranged on a hand;

FIG. 5 is a third perspective view thereof arranged on a hand;

FIG. 6 is a fourth perspective view thereof arranged on a hand; and,

FIG. 7 is a fifth perspective view thereof arranged on a hand gripping a handle.

The broken lines shown in the drawings are included for the purpose of illustrating portions of a hand and handle that form no part of the claimed design.

1 Claim, 5 Drawing Sheets
